(57) **CLAIM**

The ornamental design for a bayonet-mount oven-light lens, as shown.

DESCRIPTION

FIG. 1 is a perspective view from above of the bayonet-mount oven-light lens according to the invention;

FIG. 2 is a view like FIG. 1 but with the lens upside-down;

FIG. 3 is a front elevational view of the lens;

FIG. 4 is a top view of the lens;

FIG. 5 is a rear elevational view of the lens; and,

FIG. 6 is a bottom view of the lens.
